MAGNETIC TAPE APPARATUS

Francis A. Fary, Palo Alto, Calif., assignor to Ampex Corporation, Redwood City, Calif., a corporation of California

Filed Nov. 28, 1960, Ser. No. 62,995

Term of patent 14 years

(Cl. D26—14)

FIGURE 1 is a front perspective view of a magnetic tape apparatus in accordance with my new design;

FIGURE 2 is a side elevational view of FIGURE 1, the other side being the mirror image thereof; and

FIGURE 3 is a top plan view of FIGURE 1.

The back of the magnetic tape apparatus is conventionally plain.

I claim:

The ornamental design for a magnetic tape apparatus, substantially as shown and described.
